DEEP WELL PUMP

Julius Paul, Duluth, Minn., assignor of one-half
to Richard M. Sellwood, Duluth, Minn.

Application May 15, 1935, Serial No. 21,595

19 Claims. (Cl. 103—46)

This invention relates to hydraulically operated fluid pumps for use in raising water or oil or other fluids from deep bored wells and operated by fluid pressure from the surface.

5 The principal object of the invention is to provide a double acting motor and pumping cylinder for such a pump actuated by a rotatable valve.

10 Another object is to provide a novel form of rotatable valve for controlling the various ports for such a pump.

15 Still other objects and advantages of the invention will appear in the following description thereof.

20 Referring now to the accompanying drawing forming part of this application, and wherein like reference characters indicate like parts:

25 Figure 1 is a central vertical cross-sectional view of my improved deep well pump, partly in elevation.

Figures 2, 3, 4, 5, 6, 8 and 12, are, respectively, slightly enlarged cross sectional views on the lines 2—2, 3—3, 4—4, 5—5, 8—8, and 12—12, of Figure 1.

30 Figure 7 is a top plan view of the motor piston.

Figure 9 is a perspective view of a fragmental portion of the rotatable valve illustrating the cam formed thereon for rotating the valve.

Figure 10 is a perspective view of the arcuately 35 shaped valve shoe.

Figure 11 is a cross-sectional view on the line 11—11 of Figure 4, showing the finger 14, shoe 50, and cooperative parts in elevation.

40 My combined motor and pump structure is designed to be installed within the well casing, not shown, and is of a diameter to just conveniently fit therein without binding. Also within the casing are axially disposed a pair of pipes the full length thereof, and the lower ends of which pipes are indicated at 1 and 2, the latter being installed within the former and through which the power fluid is forced for operating the motor piston as hereinafter described and within the pipe 1 the 45 exhaust power fluid together with the fluid pumped is forced to the top of the well. To the lower ends of these pipes 1 and 2 is screw threaded applied the solid block 3, it having a pair of openings therein, 4, which is arcuate in shape and communicates with the pipe 1, and 5 which 50 communicates or registers with the power fluid pipe 2.

To the lower end of this block 3 is bolted or otherwise removably fixed the head block 6, which is provided with an arcuately shaped opening 7 communicating with the opening 4 at its up-

per end. There is also provided another arcuately shaped opening 8, which communicates with but is much longer than the opening 5. In depth this opening 8 extends downwardly in the block 6 but about one-fourth its length, and from thence downwardly a pair of openings are formed, one communicating with each end of the bottom of the opening 8, the pair of openings being indicated at 9 and 10, and they are inclined and converge downwardly into the single opening 11.

This head 6 is also provided with an axial bore into which extends the double-walled rotatable valve 12, the inner wall of which projects above the outer wall and to the upper end of the block 15 6, its extreme uppermost end being solid, and about which solid portion is keyed the sleeve 13 having a laterally extending finger 14 formed integral therewith and extending within the opening 8. It is to be understood that this double 20 walled valve 13 is susceptible only of rotary motion for alternately opening and closing the valves which control the operation of the pump.

To the lower portion of the head block 6 is 25 screw-threadedly attached as at 15 the motor cylinder 16, and to the lower end of this motor cylinder is similarly screw-threadedly attached as at 17 the intermediate block 18, a more detailed description of which will be set forth later. Within the motor cylinder 16 is reciprocably 30 mounted the hollow piston 19 which snugly fits within the cylinder 16 and also fits externally of the double walled rotatable valve 12. This piston is fixed as by a pair of opposed bolts, indicated at 20, which extend downwardly through 35 the intermediate block 18 and are attached to the pump piston 21 mounted within the pumping cylinder 22, screw threadedly attached to the lower end of the intermediate block 18, and within 40 which cylinder the pumping piston snugly fits as well as fitting about the rotatable valve 12, which latter also extends clear through the intermediate block 18, the pumping cylinder 22, and into and through the foot block 23, which latter is screw-threadedly attached as at 24 to the 45 pumping cylinder 22; the rotatable valve 12 being freely rotatable within the foot block 23, intermediate block 18 and head block 6. But by virtue of the bolts 20 extending through the intermediate block 18 and connecting the pistons 50 19 and 21, these pistons are non-rotatable, the object of which will appear later.

55 It will be noted that the double walled rotatable valve 12 has two sets of ports therein, one for control of the motor operating mechanism and

the other for the control of the pumping mechanism, and that the innermost tubular portion of the valve is divided into an upper and lower chamber 25 and 26 by virtue of the division wall 27.

The power receiving ports in the upper end of the rotatable valve 12 communicating with the inner tubular chamber 25 thereof are indicated at 28 and 29, the former being in constant communication with the channel opening 11, and the latter susceptible to opening and closing during the rotation of the valve to supply power intermittently to the top of the piston 19; while the power receiving port at the lower end of the chamber 25 is illustrated at 30 which intermittently communicates with the port 31 in the intermediate block 18 for intermittently supplying power fluid to the under side of the piston 19; the port 29 communicating with the opening or passageway 32 in the block 6 for admitting the power fluid to the top of the piston. It will be noted that the ports 29 and 30 are formed through closed or thimble like portions of the inner and outer walls of the valve 12 so that they do not communicate with the space intermediate of the two walls of the valve. The discharge port at the upper end of the outer wall of the valve 12 is shown at 33, it remaining at all times open and in communication with the passageway 7 in the head block 6, and through which port and passageway all of the fluid pumped as well as the exhaust fluid from either side of the motor piston 19 passes on its way to the surface of the well. To provide for the escape of the exhaust power fluid from either side of the motor piston I have shown the passageway 35 in the head block 6 which intermittently communicates with the port 34 in the near side of the outer wall of the valve, and the passageway 37 in the intermediate block 18 which intermittently communicates with the port 36 in the outer wall of the valve; the intermittent communication of these passageways and ports being accomplished of course by the rotation of the valve 12, and which also directs the power fluid alternately above and below the piston for reciprocating the same.

Since this double walled valve 12 extends through the pump cylinder, and the pump piston 21 is rigidly connected to the motor cylinder, ports and passageways for the double action of said pump must be provided within the valve, the intermediate block 18, and the foot block 23 for the proper functioning of the pump. There is a solid wall or thimble-like construction 38 intermediate of the inner and outer walls of the valve 12 and within the intermediate block 18 and through which the port 39 is formed, which intermittently communicates with the passageway 40 in the block 18 by rotation of the valve. Since the port 39 communicates with the inner chamber 26 of the valve, which chamber extends downwardly through the foot block and into the body of oil or other fluid to be pumped, when the piston 21 is forced downwardly by the motor piston, fluid will be sucked up the chamber 26, through the port 39 and passageway 40 into the cylinder 22 above the piston 21. Within the foot block 23 is formed a passageway 43 which intermittently communicates with a port 55, identical with the port 39, extending through the double walls of the valve and to the inner chamber 26 thereof, so that when the pump piston is moving upwardly fluid will be sucked up the chamber 26, through the port 55 and passageway 43 into the cylinder 22 below the piston 21. When the piston 21 has

reached the upper end of its stroke and consequently has filled the cylinder 22 with oil below the piston and the latter is about to descend, the rotation of the valve will have opened communication between the passageway 44 in the foot block 23, and the port 56 into the space between the inner and outer walls of the valve, so that as the piston descends the fluid below it in the cylinder 22 will be forced through the passageway 44, port 56, into and up through the space between the inner and outer walls of the valve through the port 33 and on up to the surface of the well. Likewise when the piston 21 reaches the bottom of its stroke and is about to ascend, the rotation of the valve will have opened communication between the port 41 through the outer wall of the valve and the passageway 42 to the cylinder 22 above the piston, so that when the piston ascends the fluid thereabove will be forced out the passageway 42, port 41 into and up through the space between the inner and outer walls of the valve and through the port 33 to the surface of the well, and thereby providing for the double action of the pump.

The smaller tubular portion of the valve extends through the lower end of the foot block 23 where it is provided with a suitable stuffing gland as at 45, and below which may be installed any desired form of screen through which the material to be pumped is drawn into the chamber 26 of the valve and thence to the pump.

For the proper control and timed rotation of the valve 12, it will be noted that cooperative cam-like surfaces as indicated at 46 in Figure 9, and 48 in Figure 10, are integrally formed about the exterior of the outer wall of the valve 12, the former engaging within a similarly shaped cut-away cam-surface 47 within the interior of the piston 19 for the initial rotation of the valve in one direction; and the latter (48) engaging with in a similarly shaped cutaway cam-surface 49 in the pump piston 21 for the subsequent rotation of the valve in the other direction.

It is obvious that such a reciprocable pump and motor, dependent upon a central rotative valve common to both (which is deemed novel in the art) may be susceptible at times to inoperativeness due to its stopping on dead center. To provide against this possibility I have installed beneath the finger wing 14 of the throttle the freely slideable arcuately shaped shoe 50 having upwardly projecting end portions 51 alternately engageable by the wing so that when the valve is rotated in either direction it will, by engaging one or the other of the flanges 51 of said shoe, carry the latter with it to close either one or the other of the ports 9 or 10. It will be readily apparent that the cam mechanism previously described operable adjacent either end of the stroke of the pistons, will carry the wing 14 sufficiently beyond a central position to permit of the pressure of the power fluid in the port 8 acting against the wing to force it to the limit of its movement in that direction, and thus absolutely prevent any possibility of the motor or pump stopping on dead center.

The operation

Assuming that the device is properly connected to the pipes 1 and 2 and installed within a suitable casing within a well from which oil is to be pumped and the lower end of the rotary valve is within said body of oil. Also, while I have illustrated in some of the views the motor and pump pistons as having made a partial stroke,

for convenience in description of the various parts, we will now assume that the pistons are at their uppermost position ready for a downward stroke. At this time the finger 14 would have been thrown clockwise (see Fig. 4) to the limit of its movement in that direction which would close communication to the motor piston through the port 9 and leave the port 10 fully open. It will be understood that this specific arrangement of ports and wing finger 14 is solely for the purpose of preventing the motor from becoming stalled on dead center; otherwise the power fluid would be free to enter the motor uncontrolled.

With the various parts in their thus assumed positions, power fluid would enter down through the openings 5, 10, and 11, through the port 28 into the inner chamber 25 of the rotary valve, and downwardly to and through the port 29 and passageway 32 into the motor cylinder 16 above the piston 19 forcing it downwardly and at the same time forcing downwardly the pump piston 21. Now as the two pistons move downwardly exhaust from the motor piston will pass through the passageway 37 and port 36 into the space between the double walls of the valve 12 and upwardly and out through the port 33 into the passageway 7 and through the opening 4 into the space between the pipes 1 and 2 and on up to the top of the well. Simultaneously the pump piston 21 in its downward movement will force the oil beneath same through the passageway 44 and port 56 into the space intermediate of the two walls of the valve and force it upwardly, joining the exhaust from the motor and be discharged from the surface of the well. Also as the pump piston goes down oil to be pumped will be sucked up through the inner chamber 26 through the port 39, passageway 40 and into the cylinder 22 above the piston.

Now as the motor piston 19 approaches the lower end of its stroke, its interior cut-out cam-like portion 47 will engage the cam 46 on the periphery of the valve 12 and cause the same to be rotated in an anti-clockwise direction until the finger wing 14 has closed communication through the port 10, it being noted that at such time the shoe 50 has not yet been moved and still holds the port 9 closed. However the instant this happens the pressure of the power fluid against the inner side of the finger wing will continue its swinging motion carrying with it the shoe and thus instantly open the port 9 thereby permitting the fluid to continue entering the tubular chamber 25. But, at this time, due to the rotation of the valve the port 29 will have been closed and the port 30 opened causing the power fluid to pass therethrough and through the passageway 31 forcing the piston 19 in the opposite direction; also the port 36 will have been closed and the port 34 opened permitting the exhaust above the piston to escape up through the port 33, passages 7 and 4 to the well surface. At this same time the pump cylinder will be on its upward stroke and the port 56 will have been closed and the port 41 opened so that the oil above the piston will be forced through the passage 42, port 44 into the space between the walls of the valve and join the exhaust from the motor piston in their travel to the surface of the well. And then as the pump piston 21 approaches the upper limit of its stroke its internal cut-out cam-like portion 49 will engage the cam 48 on the periphery of the valve, reversing the rotation of the valve, closing and opening the

various ports to cause the motor piston to be forced downwardly again.

Having thus described my invention, what I claim and desire to secure by Letters Patent, is:

1. In a double acting pump, two concentric longitudinally spaced cylinders, a rotatable valve axially disposed within said cylinders, a piston within each cylinder connected together to operate in unison and reciprocable about said valve, means on said valve cooperative with means on one piston to operate the valve to control pressure fluid to opposite sides of one piston to reciprocate same, and means on said valve cooperative with the other piston to operate the valve to control the flow of the liquid pumped. 15

2. In a double acting fluid pressure pump, a power fluid supply, two concentric longitudinally spaced cylinders, one of which is a power cylinder, a rotatable valve axially disposed within said cylinders, a piston within each cylinder and reciprocable about said valve, one of said pistons being a power piston, means for causing said pistons to move in unison, means for rotating the valve to control the intake and exhaust of the power fluid, to and from said power piston. 25

3. In a fluid pump, a cylinder, a hollow rotatable valve axially disposed within said cylinder, a piston reciprocable upon said valve for pumping the fluid into and from said cylinder through said hollow valve, means for reciprocating the piston, and cooperative means upon the valve and piston for rotating the valve to control the flow of the fluid pumped. 30

4. In a double acting pump, a power fluid supply, two concentric longitudinally spaced cylinders, one of which is a power cylinder, a double-walled rotatable valve axially disposed within said cylinders forming separate passageways therein for power fluid and the fluid pumped, and a piston within each cylinder connected together to operate in unison and one of which is the power piston; said valve having openings therein registerable with openings in said cylinders communicating with the space above and below said pistons. 45

5. In a fluid pump, a cylinder, a hollow rotatable valve axially disposed within said cylinder, a cam-surface formed upon the periphery of said valve, a piston reciprocable about said valve and within said cylinder, and a cam-surface within said piston engageable with the cam-surface on the valve for rotating same to control the flow of fluid pumped into and through said valve to the top of the pump. 50

6. The combination with a double acting pump having aligned reciprocal motor and pump cylinders having pistons operable in unison therein, of a hollow rotatable valve disposed axially within said pistons and upon which valve said pistons reciprocate, means alternately operable by the pistons for rotating the valve to control the flow of pressure fluid to the motor piston, and the flow of the fluid pumped during the operation of the pump, and means operable by the valve to prevent the pump stopping on dead center. 60

7. The combination with a double acting pump having aligned cooperative reciprocal motor and pump cylinders each having a piston therein operable in unison, of a rotatable valve disposed axially within said pistons and upon which valve said pistons reciprocate, means for the inlet and exhaust of power fluid to the motor piston, means for the inlet and discharge of pumped fluid from the pump piston, means alternately operable by 70

75

- the pistons for rotating the valve to control power fluid to the motor piston, and simultaneously control the flow of fluid pumped during the operation of the pump, means operable by the valve to prevent the pump stopping on dead center, and a unitary power fluid connection to said motor.
8. A double acting fluid pump comprising a fluid power supply and exhaust means therefor, a casing, portions of which form motor and pump cylinders, a piston within each cylinder connected together to operate in unison, a rotatable valve extending within each piston, means upon the valve engageable by one piston for rotating the valve to cause the power fluid to be directed alternately to opposite sides of said motor piston, and means for rotating the valve to control the flow of the fluid pumped.
9. A double acting fluid pump comprising a casing portions of which form motor and pump cylinders, a piston having an axial opening therethrough within each cylinder, said pistons being connected to operate in unison a rotatable valve axially disposed within said pistons and cylinders, a fluid power supply, exhaust means for said fluid power, and means upon the valve engageable alternately by said pistons for directing and discharging the power fluid alternately to and from opposite sides of the motor piston and simultaneously opening and closing inlet and exhaust means for fluid pumped.
10. A double acting fluid pump comprising motor and pump cylinders, a piston having an axial opening therethrough within each cylinder and operable in unison, a rotatable valve axially disposed within said cylinders and pistons, a fluid power supply, inlet and exhaust ports for the power supply, inlet and discharge ports for the fluid pumped, and means whereby the reciprocation of the pistons operates the valve to control the power fluid alternately to and from opposite sides of the motor piston and simultaneously controls the inlet and discharge ports for the fluid pumped.
11. A piston and valve structure for fluid motors, comprising a cylinder, a hollow rotatable valve axially mounted within the cylinder inlet and discharge ports communicable with the interior of said valve, a piston having an axial opening therethrough mounted and reciprocable upon said valve and within said cylinder, said piston and valve having cooperative means to rotate the valve to control the intake and exhaust of a power fluid alternately to and from opposite sides of said piston to reciprocate same, and simultaneously control the pumped fluid to and from said inlet and discharge ports.
12. In a fluid pump, a cylinder, a reciprocable piston having an axial opening therethrough within said cylinder, a hollow valve axially disposed within said cylinder extending through and rotatable within the opening in said piston, means for reciprocating the piston for pumping the fluid into and from the cylinder through said valve, and means for rotating the valve to control the flow of liquid pumped.
13. In a fluid pump, a cylinder having ports at its respective ends communicating with the interior of the hereinafter mentioned hollow valve, a pumping piston reciprocable within said cylinder for drawing fluid through said ports into said cylinder alternately at opposite ends of said piston and simultaneously discharging liquid from said cylinder alternately from opposite ends of said piston to the top of the pump, means for reciprocating the piston to pump the fluid, and a

hollow valve within said cylinder operable by the movement of the piston to control the ports and thereby regulate the flow of the fluid pumped through said valve.

14. In a fluid pump, a cylinder, a piston having an opening therethrough reciprocable within said cylinder, a double walled valve extending through said opening and upon which said piston reciprocates, ports through both walls of the valve and communicable with said cylinder for drawing fluid into the cylinder alternately at opposite ends of said piston, ports through the outer wall of the valve and communicable with said cylinder alternately at opposite ends of said piston for receiving liquid from said cylinder and conducting it between the walls of the valve to the top of the pump, means for reciprocating the piston to pump the fluid, and means for operating the valve to control the ports to regulate the flow of the pumped fluid.

15. In a fluid pump, a cylinder, a hollow rotatable valve within said cylinder, a piston having an opening therethrough through which the valve extends and upon which valve the piston is reciprocable within the cylinder, intake and exhaust ports communicating alternately with said cylinder, means for reciprocating the piston to pump the fluid through said ports and valve into and from said cylinder, and cooperative means upon the valve and piston for rotating the valve to control the flow of the fluid pumped.

16. In a fluid motor, a cylinder, a hollow rotatable valve within the cylinder, a piston having an opening therethrough through which the valve extends and upon which the piston is reciprocable within the cylinder, a fluid power supply, inlet and exhaust ports for the fluid power supply, and cooperative means associated with the piston and valve to rotate the valve to control the intake and exhaust of the power fluid through said valve alternately to and from opposite sides of said piston to reciprocate same.

17. In a fluid motor, a cylinder, a rotatable valve within the cylinder, a piston having an opening therethrough through which the valve extends and upon which the piston is reciprocable within the cylinder, a fluid power supply, inlet and exhaust ports at opposite ends of the cylinder for the fluid power supply, cooperative means associated with the piston and valve to rotate the valve to control the intake and exhaust of the power fluid alternately to and from opposite sides of said piston to reciprocate same, and means operable by the valve to prevent the piston stopping on dead center.

18. A piston and valve structure for pumps, comprising a reciprocable piston having an opening therethrough, a cam surface formed in the wall of said opening, a rotatable valve extending within said opening and upon which valve said piston is reciprocable, and a cam surface on the periphery of said valve for cooperation with the cam surface within said piston for rotating the valve when said cam surfaces cooperatively engage one another.

19. In combination, a cylinder, a pump piston reciprocable within the cylinder, a hollow valve for control of liquid therethrough to and from said cylinder, said valve controlling passageways for said liquid and being rotatably mounted within said piston, said piston being freely reciprocal upon said valve, and means whereby the valve is rotated at the termination of the stroke of the piston in either direction.
